Primary Examiner — Michelle E. Wilson*Assistant Examiner* — Tracey J Bell(74) *Attorney, Agent, or Firm* — Workman Nydegger(57) **CLAIM**

The ornamental design for a garbage can, as shown and described.

DESCRIPTION

1. Garbage can

1.1 is a perspective view;

1.2 is a front view;

1.3 is a rear view;

1.4 is a left side view;

1.5 is a right side view; and

1.6 is a top view.

The broken lines depict portions of the garbage can that form no part of the claimed design.
